UNITED STATES PATENT OFFICE.

FRED E. FRANK, OF NEW YORK, N. Y., ASSIGNOR TO HENRY A. DIX & SONS CORPORATION, OF NEW YORK, N. Y., A CORPORATION OF NEW YORK.

GARMENT.

Application filed April 25, 1924. Serial No. 708,929.

To all whom it may concern:

Be it known that I, FRED E. FRANK, a citizen of the United States, and a resident of New York, in the county of Bronx and 5 State of New York, have invented certain new and useful Improvements in Garments, of which the following is a specification.

This invention relates to garments and more particularly to washable dresses and 10 the like, and has for one of its objects to provide garments of this kind with means whereby buttons or other fastening devices may be easily removed from them, prior to laundering, so that they will not be 15 subjected to breakage, or, if made of metal, will not impart rust spots or other discoloration to the garment.

Another object is to provide means for detaching or attaching these fastening devices which connect each individual device 20 and which means are simple in construction, achieving their purpose easily and quickly.

Other objects will be more fully described in the following specification and will be 25 apparent in the accompanying drawings illustrating a preferred form of the invention and in which,

Fig. 1 is a fragmentary elevational view 30 of a dress embodying the invention;

Fig. 2 is an enlarged fragmentary longitudinal sectional view taken along the plane of line 2—2, in Fig. 1;

Fig. 3 is an enlarged fragmentary cross-sectional view taken along the plane of line 35 3—3, in Fig. 1; and

Fig. 4 is a perspective view of the fastening means proper.

Like characters of reference denote similar parts throughout the several views and 40 the following specification.

10 is a dress, having a body portion 11, sleeves 12, and a shawl collar 13. Dress 10 has a slit 14 extending downwardly in front from collar 13 to, preferably, knee length, 45 at 15 forming a placket. This slit is covered by a panel 16, extending downwardly the full length of the dress, having open flaps or box plaits 17 and 18, at both sides. The side of the panel with flap 18 projects over and beyond the slit 14, and has an upper end 19 below the collar 13. A part 20 of the front of the dress, forming its edge and being directly flap 18, is provided with button holes 21, equidistant from each other. 50 22 are button holes, registering with holes

21, through a part 23 of the dress 10, lying directly underneath part 20 of the outer portion of the dress and being covered by it.

24 is a narrow tape of cloth or other suitable material having sewed thereon a number of buttons 25, by means of threads 26. These buttons 25 are equidistant from each other and from ends 27 of tape 24, leaving equal spaces 28 between each other and equal spaces 29 between them and the ends 27. 60

The application and use of the tape 24 is obvious. The buttons 25 are inserted through button holes 22 into the part 23 of the dress 10. To close the front of the dress, the buttons 25 are then inserted through the 70 holes 21 into the front part 20 of the dress, below flap 18. This completely closes the dress and covers the slit 14, the flap 18 in turn covering the buttons 25, and, in combination with flap 17, imparts to the front of 75 the dress a neat and symmetrical appearance.

In practice this invention is applied particularly to washable dresses. The tape 24 with buttons 25 is easily applied. Before laundering, the tape is quickly removed and breakage of buttons 25 prevented. If buttons are made of metal, or of material which is colored, their removal eliminates discoloration of the dress due to rust or the like, while undergoing laundering processes. The tape 24 is customarily made of washable material, so that the same may be cleaned independently of the dress, if so desired. 80

Attention is particularly called to the fact 90 that the distances between the buttons on the tape are equal and also that the distances between them and the ends of the tape are equal, whereby the tape is reversible lengthwise and can easily be attached to the dress 95 without matching particular buttons with particular button holes.

While I have shown and described in the foregoing specification a preferred form of 100 the invention, it is understood that the same is susceptible to various modifications; so, for instance, while illustrated in connection with buttons sewed on a tape, any other form of fastening device may be used thereon, such as hooks, for example, engaging cloth eyes in the dress; or metal eyes may be fastened to a similar tape inserted between flap 18 and part 20, and connection between the hooks and eyes effected through 105 holes 21 and 22, allowing removal of both 110

hooks and eyes. Furthermore, the attaching of the tape to the front of the dress is only one of its many modes of application, insomuch as the same principle can be applied to any other part of the dress, and also to cuffs, belts, and the like. It is therefore obvious that various changes of form, proportion and minor details may be resorted to without departing or sacrificing any of the advantages of the invention, as defined in the appended claims.

What I claim as new, is:

In a garment, a longitudinally disposed placket formed by overlapping inner and outer portions, each having a series of equidistant button holes in register with each other, the said outer portion being provided with an extension at its top having one of the said button holes located therein, a fabric tape having buttons securely fastened

thereto, equidistant from each other, the said tape being secured to the garment by insertion of its buttons through the series of button holes in the inner portion of the said placket and having its buttons cooperating with the button holes in the outer portion of the said placket for the purpose of closing the same, one of the said buttons cooperating with the button hole in the extension of the outer portion and its registering button hole in the inner portion, and a flap at the outside of the garment covering the said buttons.

In testimony whereof I have hereunto set my hand and seal in presence of two subscribing witnesses.

FRED E. FRANK. [L. S.]
